UNITED STATES PATENT OFFICE.

WALKER G. BROWNE, OF ATLANTA, GEORGIA, ASSIGNOR TO THE UNITED STATES AUTOMATIC WATER CUT-OFF COMPANY.

AUTOMATIC CUT-OFF VALVE.

SPECIFICATION forming part of Letters Patent No. 360,140, dated March 29, 1887.

Application filed October 26, 1886. Serial No. 217,292. (No model.)

To all whom it may concern:

Be it known that I, WALKER G. BROWNE, a citizen of the United States, residing at Atlanta, in the county of Fulton and State of Georgia, have invented a new and useful Automatic Cut-Off Valve; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to the class of thermal valves that are closed automatically by the torsional motion of a compound coil that is composed of two metals having different expansive properties, the compound coil being actuated by a change of temperature, the object being to prevent the freezing of water-pipes by shutting off the supply on the approach of the freezing degree of temperature; and it consists of a valve having a weighted lever in suspense, which is released and allowed to fall at the desired temperature by the action of a compound coil, as will be herein-after fully described.

In the accompanying drawings, Figure I is a side view showing the valve, its weighted lever, and the suspending device. Fig. II is an end view showing the same. Fig. III is an end view somewhat enlarged of the weighted lever and suspending-catch. Fig. IV is a side view of the same, being all in longitudinal vertical section except the catch. Fig. V is a side view of the casing that contains the compound coil and forms the weight and the end of the sustaining-catch, showing the catch reversed. Fig. VI is a section of the compound coil.

In these figures like reference-marks refer to like parts.

1 is a valve, which is provided with an actuating-lever, 2, on the outer end of and attached to which is a hollow weight, 3. This hollow weight is firmly attached to the larger part of the valve-lever 2, and runs freely on the journal 4 at its end; also firmly attached to the valve-lever is the compound coil 6.

The other end of the compound coil has a lug, 8, attached by the plate 9, which extends outwardly a sufficient distance to engage the catch 10. The plate 9 is journaled on the lever and keeps the free end of the coil in a definite position. The relative positions of the catch 10 and the weight that incloses the compound coil are governed by the guiding-hooks 12. The catch 10 is pivoted to and suspended from the ring 14. The ring 14 slides on the rod 15, and is adjusted thereon by the nuts 16 and 17. The rod 15 projects from the bracket 19, which is preferably attached to the pipe by the sleeve 20.

The compound coil is composed of a metal having a high expansive quality, preferably brass, and a metal having a low expansive quality, preferably steel, one of which is wound over and brazed or otherwise fastened to the other, as shown in Figs. IV and VI.

Figs. I, II, and IV show the operative parts in the position in which they are when the valve is open. It will be observed that when in this position the lug on the end of the compound coil rests on the top of the catch 10, and sustains the lever in a horizontal position, and that to release this lever would allow it to close the valve by falling to a vertical position, which will occur whenever a change in the temperature shall, by its effect on the two different metals, have produced a sufficient torsional movement of the free end of the coil to carry the lug off of the catch, which will release the lever.

It is my intention to have the upper face of the catch, on which the lug 8 rests, of sufficient width to prevent the lug being slipped off of the catch by any natural heat when set to release the weight at any desirable degree of cold. The catch is made with a curved head, the radius of curvature of which being from the center of revolution of the valve-lever and slide within, and is controlled laterally by the guiding-hooks 12, in order that it may be held with certainty in its position and allow the guiding-hooks to pass over nearly its whole length, when it shall be necessary to lock the valve open by raising the weight until the top end of the catch will enter between the guid-

ing-hooks 12, which will pass over it nearly its entire length. The face of the catch, against which the lug 8 bears, is curved to the circle described by the lug, and both ends of 5 the catch are made alike in order that the catch may be reversed, as shown in Fig. V, to accommodate the device to the positions in which it is desirable to have the bracket 19 project downwardly.

10 The bracket may be attached to a vertical pipe or other object so long, and it suspends, as described, the weighted valve-lever in a horizontal position.

It is obviously necessary to adjust the releasing mechanism to allow the lever to drop at the desired temperature, which I do by changing the position of the ring to which the hook is pivoted by the nuts 16 and 17, thereby changing the relative position of the catch to 20 the lug 8.

As more power is needed to start the lever than to carry it after being started, I make the hole through the lever larger than that part of the valve-stem to which it is attached, as shown 25 in Fig. I, for the purpose of allowing the

weight to drop slightly and engage with the valve stem after having acquired extra force by its momentum.

Having thus described my invention, what I claim as new, and desire to secure by Letters 30 Patent of the United States, is—

1. In an automatic cut-off valve, the combination of the valve, its actuating-lever, a compound thermostatic coil having a lug on its free end, a weight encircling said coil to actuate the lever, and a restraining-catch operated by said coil, substantially as set forth. 35

2. In an automatic cut-off valve, the combination of a valve having a weighted actuating-lever carrying a compound coil having a lug 40 on its free end and a restraining-catch, and means of adjustment consisting of the ring 14 and nuts 16 and 17, substantially as described.

In testimony whereof I affix my signature in presence of two witnesses.

WALKER G. BROWNE.
